(57) CLAIM

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; FIG. 7 is a front view thereof shown in an environment of use; FIG. 8 is a rear view thereof shown in an environment of use; and, FIG. 9 is a right side view thereof shown in an environment of use. The dots on the legs of the garment shown in broken lines in FIGS. 1, 3, 4, 5, 7, and 9 do not form part of the claimed design. The broken lines shown at the bottom of the side pockets of the garment in FIGS. 1, 3, 4, 5, 6, 7, and 9 represent bonding, stitching, or the like and form part of the claimed design. The broken line showing of the feet, arms, and torso in FIGS. 7-8 and the item in the side pocket of the garment in FIG. 9 is for the purpose of illustrating portions of the environmental structure and forms no part of the claimed design.
